UNITED STATES PATENT OFFICE.

JOSEPH KAUFFMAN AND JOHN J. KAUFFMAN, OF PHILADELPHIA, PENNSYLVANIA.

FOLDING CLOTHES-RACK.

SPECIFICATION forming part of Letters Patent No. 416,843, dated December 10, 1889.

Application filed July 25, 1889. Serial No. 318,687. (No model.)

To all whom it may concern:

Be it known that we, JOSEPH KAUFFMAN and JOHN J. KAUFFMAN, both citizens of the United States, residing at the city of Philadelphia, in the county of Philadelphia and State of Pennsylvania, have invented certain new and useful Improvements in Folding Racks, of which the following is a specification, reference being had to the accompanying drawings, forming part thereof, and in which—

Figure 1 is a rear elevation of a portion of the head-board of a bedstead with our improved folding clothes-rack applied thereto, that is in full lines in a concealed position and in dotted lines in a position for use. Fig. 2 represents a detached elevational view of the folding rack, showing the supporting-arm with its projecting hooks detached and the bracket to be applied to the piece of furniture; and Fig. 3 is a side elevation of our improved folding rack with the projecting hooks removed, and in which view the device in full and in dotted lines is shown in the respective positions the same occupies when concealed and in position for use.

The principal object of our invention is to provide an improved clothes-rack of not only simple construction, but also cheap, compact, and durable, and a rack which may be readily attached to a piece of furniture in such manner as that when in use the same affords a firm support for clothing and other articles, and when not in use may be folded down and concealed from view.

The nature and characteristic features of our invention will be more fully understood taken in connection with the accompanying drawings and the following description, in which—

A is a horizontal arm of any preferred form, with a rear projecting tongue a' and front projections b and b' .

B, B', and B² are three hooks of any preferred construction, but with preferably their rear ends enlarged, with lugs c , c' , and c^2 cast therewith or secured thereto. These hooks

B, B', and B² are, by means of a pivot d , connected with the projections or shoulders b and b' of the arm A. In the arm A is provided a

horizontal slot e , which is curved and enlarged in size at its rear end, for a purpose to be presently explained.

F is a bracket, preferably constructed curvilinear in form at the top and with the rear side cut away at f . This bracket is provided with a rear projecting lug f' . In this bracket are holes f^2 for the reception of screws f^3 , in order to secure said bracket rigidly to a piece of furniture.

g is a pin or screw passing through the slot e of the arm A into the body of the bracket F.

The mode of operation of our improved folding rack for clothes, &c., is as follows: The bracket F is rigidly secured to the rear portion of the piece of furniture or head-board of the bedstead. The arm A is in pivotal connection with the bracket F by means of the pin or screw g and affords a freedom of movement through the horizontal slot e of said arm. When the rack is desired for use, the same may be readily moved by hand from its concealed position, which is indicated by the full lines in Fig. 1, to the position indicated in dotted lines in the same figure by simply causing the tongue a' of the arm A to engage with the rear surface of the lug f' and with the pin or screw g , thereby assuming a position in the enlarged slot e , as shown in Fig. 3, when the hooks may be readily extended to the desired position for the reception of the articles of clothing or apparel. The lugs cast with or secured to the enlarged rear portions of the hooks prevent undue extension thereof or their movement in a contrary direction by the contact of the lugs with the surface of the arm A. When it is desired to conceal the rack from view, the arm A, with its hook, is by hand raised slightly, so as to free the annular portion of the slot e from the pin or screw g , and the device is then slid along sufficiently to disengage the lug f' of the bracket F from the tongue a' of the arm A to permit of the same being readily concealed from view behind the piece of furniture.

Having thus described the nature and objects of our invention, what we claim as new, and desire to secure by Letters Patent, is—

1. In a folding clothes-rack, an arm pro-

vided with shoulders and hooks having lugs pivoted thereto, in combination with a bracket having a lug and a pin or screw to hold said shouldered arm in position, substantially as and for the purposes described.

2. The combination, in a folding rack, of a horizontal shouldered arm provided with a slot and a tongue, hooks having lugs pivotally connected with said arm, and a bracket having the rear portion cut away, and a pin

or screw secured to said bracket, substantially as and for the purposes described.

In witness whereof we have hereunto set our hands in the presence of two subscribing witnesses.

JOSEPH KAUFFMAN.
JOHN J. KAUFFMAN.
